UNITED STATES PATENT OFFICE.

WALTER R. PEOPLES, OF ROCHESTER, NEW YORK.

DESIGN FOR A TOY VEHICLE.

55,434.

Specification for Design.

Patented June 8, 1920.

Application filed March 6, 1920. Serial No. 363,836. Term of patent 14 years.

To all whom it may concern:

Be it known that I, WALTER R. PEOPLES, a citizen of the United States, residing at Rochester, in the county of Monroe and State of New York, have invented a new, original, and ornamental Design for Toy Vehicles, of which the following is a specification, reference being had to the accompanying drawings, forming part thereof.

Figure 1 is a side elevation of a toy vehicle, showing my new design.

Fig. 2 is a top plan view of the same.

I claim—

The ornamental design for a toy vehicle, as shown.

WALTER R. PEOPLES.
